DESIGN FOR A SHOE

Josephine Davies, New York, N. Y., assignor to Bancroft-Walker Company, Waltham, Mass., a corporation of Massachusetts

Application June 6, 1936, Serial No. 63,054

Term of patent 3½ years

To all whom it may concern:

Be it known that I, Josephine Davies, a citizen of the United Kingdom of Great Britain, residing at New York, in the county of New York and State of New York, have invented a new, original, and ornamental Design for a Shoe, of which the following is a specification, reference being had to the accompanying drawing forming a part thereof, in which,

Fig. 1 is a plan view of a shoe showing my new design,

Fig. 2 is a view of the shoe in side elevation.

I claim:

The ornamental design for a shoe substantially as shown.

In witness whereof, I have affixed my signature hereto.

JOSEPHINE DAVIES.
